ELECTRICAL CONTROL SYSTEM

Malcolm H. Sheldon, New York, N. Y.

Application February 15, 1946, Serial No. 647,982

7 Claims. (Cl. 315—320)

(Granted under the act of March 3, 1883, as
amended April 30, 1928; 370 O. G. 757)

1

This invention relates to electrical control systems and more particularly to control systems for lighting airplane taxiways. In a copending application submitted by the present inventor entitled "Runway lighting control," Serial Number 624,621, filed October 25, 1945, a novel control system and panel for airplane runways is shown and described. The particular problems of taxiway-lighting control differ from the problems involved in runway-lighting control.

An object of the present invention is to provide an improved electrical control system for the lighting of airplane taxiways.

Another object is to provide a control circuit that insures correct operation of the taxiway-lighting system.

A further object is to provide a simple and easily operable control panel for the taxiways-lighting system.

Further objects and advantages of this invention, as well as its construction, arrangement and operation, will be apparent from the following description and claims in connection with the accompanying drawing, in which

Fig. 1 is a diagram of the electrical circuit of the present invention.

Fig. 2 is a perspective view of the control panel that forms part of the present invention.

There is shown above the dotted line 10 that portion of the electrical circuit that is housed in the control panel 11 shown in Fig. 2. The control-panel circuit includes a plurality of momentary contact pushbuttons 12, one pushbutton 12 for each taxiway on the airfield. A pilot light 13 and nameplate 13' are associated with each pushbutton 12. A switch 14 completes the major electrical elements within the control panel 11 and it also has its corresponding pilot light 13 and nameplate 13'.

The electrical elements comprising the field circuit, shown below the dotted line 10, include taxiways selector relays 16 coils 15 of which, when energized, simultaneously open the normally closed relay contacts 17 and close the normally opened relay contact 16, a protective relay 24, a constant current transformer 22, a remote-controlled oil circuit breaker 18 having normally opened primary contacts 19 and a normally closed control contact 20, and a fused primary cutout 25. The primary circuit or high-voltage circuit that supplies power to the multiple banks of lamps, which line the sides of each airfield taxiway, includes a primary source of high-voltage power 21, the primary circuit breaker 18, a constant current transformer 22, the normally

2

closed relay contacts 17, one for each bank of lamps (schematically shown as resistances 23) on each taxiway, a protective relay 24, and a fused primary cutout 25, which is normally closed.

Operation of the control panel 11 is as follows. Prior to the selection of a taxiway, the control panel 11 is not energized and the circuit is as shown in Fig. 1 save that fused primary cutout 25 is closed. A taxiway or combination of taxiways is selected by momentarily pressing the corresponding pushbuttons 12. The single-pole double-throw switch 14 accomplishes a dual purpose, namely, to open or close oil circuit breaker 18 or to "erase" or "trip out" taxiway relay selections. If thrown to "relay trip" position (Fig. 2), it returns to "off" position, as the single-pole double-throw switch is spring actuated to return to its "off" position. When the pushbuttons 12 are pushed in to make momentary contacts, the selector relay coils 15 corresponding to the chosen pushbuttons 12 are energized, causing relay contacts 16 to make contact with their corresponding relay contacts 28 and also causing relay contacts 17 to open. The opening of contacts 17 removes the shunt across the bank of lamps 23 so that the lamps light up when the primary circuit breaker contacts 19 are closed.

At this stage, the energized relays 16 are holding their corresponding lamp circuits open, the holding circuit being maintained across the normally closed auxiliary contacts of switch 26. Once the taxiway selection has been made, the arm 29 of the single-pole double-throw switch 14 is made to contact the contact 27 or the one marked "Closed." This causes the solenoid 30 to be energized; the energized solenoid 30 opens the normally closed relay contacts 20 and causes normally opened relay contacts 19 to close the primary circuit, permitting a high-voltage current to light the banks of lamps 23 that have been held in readiness by the particular selector relay coils 15 that were originally selected by the operator of the control panel 11.

If it is desired to operate a given group of taxiways for a particular night, the switch 26 will be kept in contact as shown in Fig. 1 and the primary circuit for those taxiways will be held in readiness. The taxiways are lighted by throwing the arm 29 to contact the contact 27 and are extinguished by returning the arm 29 to its "off" position; the selected taxiways are always kept in readiness unless the relay trip 26 is momentarily opened.

The circuit shown accomplishes the following: It assures that the taxiway relays 16 can

be selected only when the primary circuit breaker 18 is open. If the panel operator should inadvertently close the primary circuit, the auxiliary normally closed control relay tip or contact 20 will open, shutting off the low voltage power source to the selector relay coils 15, so that no selection of taxiways can be made. The control scheme also assures a correct sequence of operation. If the taxiways selected are incorrect, the switch 26 is pressed in the "relay trip" direction (Fig. 2), so erasing relay selection, the spring 31 returning the relay 26 back to its closed position. This momentary tripping of the relay 26 "erases" the selection of relays 16 by deenergizing the coils 15 and a new selection can now be made. Moreover, when the lighted lamps of the taxiways are extinguished, the movement of the arm 29 away from contact 27 assures that primary circuit current (high voltage current) is always broken by the oil circuit breaker's contacts 18, preventing any high voltage current from breaking across the selector relay contacts 16, consequently safeguarding them from rapid deterioration and destruction.

The protective relay 24 shuts off the primary high-voltage circuit in case a field conductor is broken by a crashing plane.

The present invention affords an extremely simple control panel for operating a plurality of taxiways to be lighted singly or in groups, so simple in fact, that a novice cannot operate it incorrectly. The control scheme shown and described affords a safe electrical interlocking between the field circuits and panel circuit and also provides a foolproof method for obtaining a correct sequence of panel operation.

No intricate electrical connections nor complicated electrical equipment is necessary, so that repairs, when necessary, can be made cheaply and quickly.

Various modifications and changes can be made in the above without departing from the spirit and scope of the invention as set forth in the appended claims.

The invention described herein may be manufactured and used by or for the Government of the United States of America for governmental purposes without the payment of any royalties thereon or therefor.

What is claimed is:

1. In a control circuit for lighting a plurality of airfield taxiways, a bank of lamps for each taxiway, a source of high voltage current for the lamps, shunt means to direct current from each bank of lamps, circuit breaking means for said high-voltage current, a plurality of solenoids associated with said shunt means, a low-voltage power source for said solenoids, momentary contact means for activating said solenoids so as to remove the shunts from said lamps, means for holding said shunts removed from the lamps, when the momentary contact means are released, and switch means for closing the primary circuit so that the selected lamps are lighted.

2. In a control circuit for lighting a plurality of airfield taxiways, a bank of lamps for each taxiway, a primary circuit for said plurality of banks of lamps, switch means in said primary circuit, shunt means across each bank of lamps, a secondary circuit including momentary contact means for removing the shunt means from preselected banks of lamps, a holding circuit whereby said preselected banks of lamps are maintained in an open condition to receive electrical energy from the primary source of power,

means for activating said switch means to close the primary circuit and light the preselected banks of lamps, and electrical interlocking means preventing any further removal of shunt means across a bank of lamps once the switch means closes the primary circuit.

3. In a control circuit for lighting the banks of lamps of a plurality of airfield taxiways, a bank of lamps for each taxiway, a primary source of electrical power for the banks of lamps, shunts across each bank of lamps, a secondary circuit including a selector relay linked to each shunt across a bank of lamps, momentary contact means for energizing preselected relays and cause said relays linked shunts to open the circuit of its associated bank of lamps, a holding circuit to maintain said preselected shunts in their open position, switch means for energizing and deenergizing said preselected banks of lamps without deenergizing the holding circuit.

4. In a control circuit for lighting the banks of lamps of a plurality of airfield taxiways, a bank of lamps for each taxiway, a primary source of electrical power for the banks of lamps, shunts across each bank of lamps, a secondary circuit including a selector relay linked to each shunt across a bank of lamps, momentary contact means for energizing preselected relays and causing their linked shunts to move away from their associated banks of lamps, indicating means for visually denoting relays that have been selected, a holding circuit to maintain said preselected shunts in their open position, switch means for energizing and deenergizing said preselected banks of lamps without deenergizing the holding circuit and without causing the primary circuit to break across the selector relays.

5. In a control circuit for lighting a plurality of taxiways in which each taxiway is lighted by a lamp circuit from a source of power, a shunt adapted to be connected across each lamp circuit, a secondary circuit including a selector relay linked to each shunt, contact means for energizing a preselected relay to cause its linked shunt to move away from its associated lamp circuit, a holding circuit to maintain said preselected shunt in its open position, switch means for energizing the preselected lamp circuit without de-energizing the holding circuit and without causing the primary circuit to break across a selector relay.

6. An electrical system for energizing a selected circuit of a plurality of circuits from a source of power, said system including a circuit having electrically operable connecting means for energizing the selected circuit from the source of power, switch means in the last circuit for operating a selected connecting means, holding means actuated by the switch means for operating the selected connecting means after the switch means is inoperative, means for energizing and de-energizing the source of power, and electrical interlocking means for de-energizing the source of power during operation of the connecting means.

7. An electrical system for energizing at least one of a plurality of electrical circuits from a primary source of power in which connecting elements are provided which are operable to energize a selected circuit from the primary source of power, said system comprising a secondary circuit having a solenoid associated with each connecting element, contact means for actuating selected solenoid to operate a selected

connecting means to energize the selected circuit from the primary source of power, holding means for actuating the selected solenoid after said contact means is released, means for energizing and de-energizing the primary source of power, and electrical interlocking means for de-energizing the primary source of power during operation of any solenoid.
